(57) CLAIM

The ornamental design for a grill, as shown and described.

DESCRIPTION

FIG. 1 is a top perspective view of a grill according to the present invention.

FIG. 2 is a bottom perspective view of the grill of FIG. 1.

FIG. 3 is a side elevational view of the grill of FIG. 1.

FIG. 4 is a side elevational view of the opposite side of the grill of FIG. 1.

FIG. 5 is an end elevational view of the grill of FIG. 1.

FIG. 6 is an end elevational view of the opposite end of the grill of FIG. 1.

FIG. 7 is a top plan view of the grill of FIG. 1; and,

FIG. 8 is a bottom plan view of the grill of FIG. 1.

The broken lines in the figures are directed to environment and form no part of the claimed design.
